(73) Assignee: **YKK Corporation**, Tokyo (JP)

(57) **CLAIM**

(**) Term: **14 Years**

The ornamental design for an adjustable fixing apparatus for a cable, as shown and described.

DESCRIPTION

(21) Appl. No.: **29/161,287**

(22) Filed: **May 24, 2002**

(30) **Foreign Application Priority Data**

Nov. 26, 2001 (JP) 2001-034470

FIG. 1 is a front perspective view of an adjustable fixing apparatus for a cable of the claimed design.

(51) LOC (7) Cl. **08-05**

FIG. 2 is a rear perspective view of the adjustable fixing apparatus for a cable of FIG. 1.

(52) U.S. Cl. **D8/356**

FIG. 3 is a front elevational view of the adjustable fixing apparatus for a cable of FIG. 1.

(58) Field of Search D2/639, 978; D8/44,

FIG. 4 is a rear elevational view of the adjustable fixing apparatus for a cable of FIG. 1.

D8/355, 356, 382, 383, 394, 395, 354;

FIG. 5 is a top plan view of the adjustable fixing apparatus for a cable of FIG. 1.

D11/200, 201, 212, 222; D28/66; 24/114.5,

FIG. 6 is a bottom plan view of the adjustable fixing apparatus for a cable of FIG. 1.

115 A, 115 H, 115 M, 115 R, 116 A, 128,

FIG. 7 is a right side elevational view of the adjustable fixing apparatus for a cable of FIG. 1, and the left side elevational view is a mirror image thereof; and,

129 B, 129 R, 130, 132 AA, 578.1, 712.9,

FIG. 8 is a front elevational view thereof on a reduced scale shown in position of use.

713, 715.4

The broken lines are for illustrative purposes only and form no part of the claimed design.
